UNITED STATES PATENT OFFICE.

EMIL R. CRECELIUS, OF PROVIDENCE, RHODE ISLAND, ASSIGNOR TO ARNOLD C. MESSLER,
OF PAWTUCKET, RHODE ISLAND.

PIN-TONGUE.

No. 905,662.

Specification of Letters Patent.

Patented Dec. 1, 1908.

Application filed May 8, 1908. Serial No. 431,560.

To all whom it may concern:

Be it known that I, EMIL R. CRECELIUS, a citizen of the United States, residing at Providence, in the county of Providence and State of Rhode Island, have invented certain new and useful Improvements in Pin-Tongues, of which the following is a specification.

My invention relates to pin tongues intended for use upon pins, brooches, badges, and similar articles of personal adornment, and has for its essential objects strength, security, simplicity, inexpensiveness, a minimum of parts, adaptability to use with catches of varying heights, and an improved spring tension of the shaft.

To the above ends essentially my invention consists in the novel construction and combination of parts hereinafter set forth and illustrated in the accompanying drawings, wherein

Figure 1 is a top plan view of the pin tongue blank. Fig. 2, a like view of the same after the blank has been bent. Fig. 3, a side elevation of my pin tongue, and Figs. 4 and 5, like elevations of the same mounted upon a pin body which is shown in central longitudinal section, the pin tongue in open and closed positions respectively.

In the drawings, A represents the pointed pin shaft, and B a transverse bar upon the end of the pin and integral therewith. The bar, B, forms lateral lugs, b, which are ultimately designed to constitute pivot members, and whose integral relation with the shaft, A, insures a maximum of strength, and a minimum of structural labor or expense to form. The described blank is shown in Fig. 1. From this blank is formed the pin tongue head in the following manner: The end portion of the shaft or stem, A, is bent to form a substantially semicircular bend or loop, c, which constitutes the rear extremity of the head. The material is continued a short distance forwardly and substantially parallel with the shaft, A, to form an unbent portion, d. The stock is then folded back upon itself to form the horizontal layer, e, which terminates in the lugs or pivots, b, and which contacts with the upper face of the

portion, d, and within the bend, c. It is preferable, but not essential, that the portions, A and e, be slightly interspaced.

The action of my pin tongue is shown in connection with the usual pin body, E, 55 catch F, and ears or joint, G. The pivots, b, are journaled in the ears, G, in any usual or convenient manner. When in closed position, the forward lower portion of the fold, e, bears against the body, E, and in conjunction with the rearward location of the pivots, b, insures the desired tension of the shaft, A, when engaged with the catch, F, as shown in Fig. 5. The lower rear portion of the loop or bend, c, forms in conjunction with the body, E, a stop for the excessive rearward travel of the tongue, A.

It will be observed both a tension and a travel stopping is furnished by the bent structure of the head, without any entangling projections. Further, that the folded portion of the head is not only simple and inexpensive to make, but provides sufficient interplay of its constituent portions to avoid undue rigidity. The sides of the head have 75 sufficient area to form convenient bearing or guiding surfaces in the cup or joint walls.

What I claim is,

1. In a pin tongue, the combination with the shaft provided with a bent end, of pivot 80 members integral with the shaft and inclosed by the bend.

2. In a pin tongue, the combination with the shaft provided at one end with oppositely directed bends, of pivot members integral with the shaft and intermediate the bends.

3. In a pin tongue, the combination with the shaft provided at one end with oppositely directed bends constituting an oblong 90 head, of pivot members integral with the shaft and intermediate the bends.

4. In a pin tongue, the combination with the shaft provided at one end with a bend, a forwardly directed straight portion extending 95 from the bend, a rearwardly directed fold upon the forward end of the straight portion, and pivot members integral with the rear end of the fold.

5. In a pin tongue, the combination with 100

a shaft provided with a bend, a fold upon the end of the bend, and integral pivot members upon the end of the fold and within the bend.

6. In a pin tongue, the combination with a shaft, of a permanently folded end portion, and pivot members integral with the shaft at the end of the folded portion.

In testimony whereof I have affixed my signature in presence of two witnesses.

EMIL R. CRECELIUS.
